Int. Cl. D10—04

U.S. Cl. D26—1

FIG. 1

FIG. 2

FIG. 3

FIG. 4

FIG. 1 is a perspective view of an electric soldering equipment matching instrument in an open position showing my new design;

FIG. 2 is a left side elevational view, the right side being a mirror image thereof;

FIG. 3 is a top plan view thereof in a closed position.

FIG. 4 is a bottom plan view thereof in a closed position.

The essential feature of my design resides in the particular arrangement of the instrument panel.

I claim:

The ornamental design for an electric soldering equipment matching instrument, as shown and described.
